Continuation of applications Ser. Nos. 257,383 and
257,384, Feb. 11, 1963. This application June 25,
1965, Ser. No. 467,060

10 Claims. (Cl. 105—366)

This invention relates to a new and improved container car and car structure particularly adapted for railway use and is a continuation of U.S. patent applications Serial No. 257,383 and Serial No. 257,384, both filed on February 11, 1963.

More specifically, the invention in one of its aspects is directed to a new and improved design of a container car permitting utilization of a full length portion as distinguished from the use of a plurality of relatively short containers mounted on the car underframe in accordance with conventional piggyback practices, the container portion being of uncomplicated construction and capable of controlled deflection in a new and improved manner with the underframe of the car under load conditions while maintaining adequate resistance to longitudinal stresses applied thereto and arising from car operational use.

In another aspect, the invention is directed to a specific form of non-rigid container of substantial length, the container being especially adapted for use as load confining means removably mounted on a flat railway car and for deflection in response to loads in uniquely cooperating relation with the railway car or other suitable vehicle means used in the support and transportation of the container.

Container systems for rail transportation have largely been derived from the basic concept of highway trailer piggyback mounting on railway flat cars. For example, emphasis has been placed on the use of containers which are interchangeable for loading purposes between a flat car and highway trailer chassis. Such containers are of rigid construction, substantially similar to railway box car body construction, with the floor, roof, end and side portions rigidly interconnected to define a single neutral axis for the container. Containers of this type have widespread use and with the availability of piggyback cars of greater length, such as on the order of 85 feet, a plurality of such containers are mounted on a single car for transportation purposes. Thus, the railway car exhibits its own operational characteristics and the individually loaded containers constitute the lading for the car.

Increasing use of container railway cars eliminates in many instances the necessity for the individual containers of a given system being adaptable for transferring to highway trailer chassis. In other words, container systems are now in some instances used exclusively by the railroads for the transportation of goods, the containers being loaded and unloaded in freight or passenger depots either while still mounted on the car or while separated from the car. The use of larger containers is preferred in view of an advantageous reduction in car loading and unloading time, thereby constituting at least a savings in labor. However, it is costly to construct large containers in accordance with conventional designs requiring individual container rigidity.

The mounting of a plurality of containers large or small on a single car of substantial length requires the spacing of the containers to a degree that total available shipping space is not fully utilized. The full utilization of available space becomes an even more important factor in connection with the widespread use of container cushioning arrangements forming a part of the car structure and functioning to isolate and protect the containers and the

2

goods therein from damaging operational forces, such as those applied to the car as a result of impact in buff or draft. Rack-type cushioning arrangements require the provision of adequate space at least at opposite ends of the car to accommodate relative movement between a car and the containers thereon during operation of the cushioning arrangement without excessive projection of the containers from opposite ends of the car. For example, it is becoming common to utilize as much as 30 inches of cushion travel in either direction thus requiring at least 30 inches of space at opposite ends of the car into which the containers can move in response to operational impacts without the containers projecting beyond the ends of the car.

15 It is an object of the present invention to provide a new and improved container car and container therefor, the container being specially constructed to lend itself to long length fabrication for use with an underframe of extended length, thus providing for single container use with a vehicle, such as a railway car.

20 Another object is to provide a new and improved container construction which incorporates uniquely arranged and functioning flexibility, whereby the container is adapted for special and unique cooperative use with an underframe.

25 Still another object is to provide a new and improved container car including as a part thereof the unique container of the invention, the container and underframe of the car cooperating in a new and improved manner under operational conditions to permit long length fabrication and utilization.

30 A further object is to provide a new and improved container of unique flexible design including as a part thereof new and improved side closure means, side closure sealing means, and roof and floor portions and end wall construction and interconnection, each of which singly and in combination constitutes a part of the invention.

35 It is another object of the present invention to provide a new and improved container system which utilizes a single full length container extending at least substantially the full length of the vehicle underframe on which it is supported, the container being of new and improved design to permit efficient operational functioning with the vehicle underframe.

40 Other objects not specifically set forth will become apparent from the following detailed description of the invention made in conjunction with the accompanying drawings wherein:

45 FIG. 1 is an exploded perspective of a container car constructed in accordance with the principles of the present invention;

50 FIG. 2 is a perspective of the container portion of the car of FIG. 1 illustrating the same with the door sections removed therefrom;

55 FIG. 3 is an enlarged transverse section of an end portion of the underframe of the car taken generally along line 3—3 in FIG. 1;

60 FIG. 4 is an enlarged cross section of a center portion of the underframe of the car taken generally along line 4—4 in FIG. 1;

65 FIG. 5 is a fragmentary perspective of one end of the container illustrating the special structure and connection of the end walls, floor and roof portions;

66 FIG. 6 is a fragmentary top plan view of the roof portion and its connection with one of the end walls;

67 FIG. 7 is an enlarged fragmentary end view of one of the pivotal connections used between an end wall and the roof portion as viewed generally along line 7—7 in FIG. 6;

70 FIG. 8 is a partly sectioned side elevational view of the connection taken generally along line 8—8 in FIG. 7;

FIG. 9 is a fragmentary perspective of the special

center pier member of the container and its attachment to the floor portion thereof;

FIG. 10 is a fragmentary side elevation of one of the intermediate spacer posts of the container illustrating its attachment to the container;

FIG. 11 is a view similar to FIG. 10 illustrating a modified form of intermediate spacer post;

FIG. 12 is a fragmentary plan view of a portion of the floor of the container illustrating a removable cover section enclosing the cushion assembly of the car;

FIG. 13 is an enlarged fragmentary end section of a portion of the cover section and adjacent floor of the container taken generally along line 13—13 in FIG. 12;

FIG. 14 is a fragmentary plan view of the cushion assembly as viewed through the floor of the container with the cover section of FIG. 12 removed therefrom;

FIG. 15 is an enlarged transverse section of the top portion of the underframe and rack assembly of the car illustrating cooperative use of cushion assembly stop members forming a part of the car;

FIG. 16 is a fragmentary perspective of one of the stop members of the underframe;

FIG. 17 is a fragmentary perspective of one of the stop members of the rack assembly;

FIG. 18 is a fragmentary transverse section of one of the door sections of the container;

FIG. 19 is a fragmentary transverse section of another of the door sections of the container;

FIG. 20 is a fragmentary transverse section of door section suspension means forming a part of the container;

FIG. 21 is a fragmentary transverse section of a door section bottom seal and guide arrangement forming a part of the container;

FIG. 22 is a fragmentary elevation of the door section bottom seal and guide arrangement of FIG. 21;

FIG. 23 is a fragmentary elevation of one form of door section lock member forming a part of the container;

FIG. 24 is a fragmentary plan view of the lock member as viewed generally along line 24—24 in FIG. 23;

FIG. 25 is a view similar to FIG. 23 illustrating operative use of the lock member;

FIG. 26 is a fragmentary elevation of another form of door section lock member forming a part of the container;

FIG. 27 is a fragmentary plan view of the lock member of FIG. 26 as viewed generally along line 27—27 therein;

FIG. 28 is a fragmentary transverse section of a door section edge sealing arrangement as viewed generally along line 28—28 in FIG. 1;

FIG. 29 is a fragmentary elevation of the edge sealing arrangement as viewed generally along line 29—29 in FIG. 28;

FIG. 30 is a view similar to FIG. 28 illustrating the door section edge sealing arrangement in its operative position;

FIG. 31 is a fragmentary section of the sealing arrangement as viewed generally along line 31—31 of FIG. 28; and

FIG. 32 is a view similar to FIG. 31 taken generally along line 32—32 in FIG. 30 and illustrating the sealing arrangement in its operative position;

FIG. 33 is a schematic illustration of a long length container car illustrated in the unloaded condition;

FIG. 34 is a schematic illustration of a loaded long length container car illustrating the deflection of such a car in the event that the same is constructed in accordance with conventional design practices;

FIG. 35 is an illustration similar to FIG. 4 illustrating the deflection characteristics of the long length container car when constructed in accordance with the principles of the present invention;

FIG. 36 is a schematic illustration of the deflection characteristics of a modified form of long length container car utilizing the principles of the invention;

FIG. 37 is a schematic illustration of the deflection characteristics of another modified form of long length container car constituting a part of the invention;

FIG. 38 is a schematic illustration of still another modified form of long length container car of the invention shown in its unloaded condition;

FIG. 39 is a view similar to FIG. 8 illustrating the deflection characteristics of the container car thereof;

FIG. 40 is a schematic illustration of still another modified form of long length container car of the invention illustrating the same in the unloaded condition; and

FIG. 41 is a view similar to FIG. 10 illustrating the deflection characteristics of the car thereof.

This invention is directed to the basic concept of long length container car construction wherein a car underframe supports container end walls which in turn are in engagement with a longitudinal container roof portion, at least one of the end walls and the roof portion being relatively movable to accommodate and provide for deflection of the container with the underframe under load conditions. The special container construction and container car design provides for substantial improvements including, among other things, the saving of substantial space, materials and cost in the fabrication and the use of the car.

The long length container car of FIG. 1 comprises a skeleton-type car 10 constituting the basic underframe structure, a long length container 11 and a cushioned rack assembly 12 which preferably forms a part of the container 11. The underframe 10 includes a longitudinal center sill structure 13 or fishbelly design supported at opposite end portions by wheel trucks 14. Opposite ends of the sill 13 suitably mount therein projecting couplers 15 associated with transverse end sill platforms 16 for use by operating personnel, etc. The sill 13 is formed with a plurality of outrigger members 17 arranged in outwardly projecting paired relation along opposite sides thereof. Each outrigger 17 mounts thereon a pair of spaced roller assemblies 18 which are aligned longitudinally of the underframe to support the container 11 and the rack assembly 12 forming a part thereof on the underframe for relative movement between the container and underframe. The center sill 13 is also provided with cushion stop members 19 arranged in longitudinally opposed relation and projecting from the top surface of the center sill.

The rack assembly 12 is formed from a pair of longitudinal rail members 20 in the form of I-beams or the like which are transversely interconnected by end angle members 21 and intermediate transverse members 22. A pair of the transverse members 22 are located relative to one another to confine therebetween a cushioning assembly 23 of known type which may include a hydraulic cylinder and cooperating return springs. The cushion assembly 23 is arranged to also be received between the stop members 19 of the center sill 13 when the rack assembly 12 is operatively positioned on the underframe in supported relation on the longitudinally aligned inboard roller assemblies 18 of the outriggers 17. The rack assembly actually constitutes a fixed part of the floor portion of the container 11 but is illustrated in FIG. 1 as separated therefrom for a better understanding of the operational mounting of the container on the underframe 10.

The container 11 includes a longitudinally continuous floor portion or base 24 which may be of any suitable construction and which preferably is flexible for deflection under load conditions with the underframe 10. The floor portion is supported longitudinally thereof by a pair of I-beams 25 located adjacent the opposite side margins of the floor portion and arranged to be received in resting engagement on the outboard roller assemblies

18 of the outriggers 17 of the underframe. As previously described, the rack assembly 12 including the beams 20 is fixed to the floor portion 24 intermediate the side beams 25 and extends longitudinally thereof. In this manner the supporting beams 20 and 25 are received on the roller assemblies 18 and the container 11 is mounted on the underframe 10 for relative movement therebetween in response to operational forces arising from impact in buff or draft. The cushion assembly 23 operates between the transverse stop or abutment members 22 of the rack assembly 12 and the stop members 19 of the underframe in the known manner to cushion the forces of operational impact to an extent that the components of such forces ultimately applied to the container 11 and the contents thereof are materially reduced or are applied in such a manner that damage to the container and contents does not occur. With this arrangement the container is movable relative to the underframe in either direction and adequate space is provided at opposite ends of the underframe to accommodate such movement. However, all of the remaining longitudinal space of the car is available for the receiving of lading within the container 11.

The container 11 includes a pair of vertical end walls 26 which are attached to opposite ends of the floor portion 24. The end walls 26 are preferably of rigid construction so that the same do not bow or otherwise flex in response to lading force applied thereto during operational use of the car. The upper ends of the end walls 26 are attached to a longitudinal roof portion 27 which is preferably flexible at least to the same extent as the floor portion 24. The extended lengths of floor and roof portions are tied together for at least substantially uniform deflection under load bearing conditions by a centrally located pier member 28, and preferably intermediate spacer posts 29. The pier member and spacer posts of course also function to support the roof portion intermediate the end walls.

The pier member in the form illustrated includes a pair of oppositely positioned rigid panels 30 extending vertically upwardly from fixed connection with opposite side marginal portions of the floor portion 24 and connected at their tops by a transverse rigid panel 31 which in turn subdivides the roof portion 27 into two segments. However, for purposes of the present invention, the roof portion 27 may be continuous throughout the length of the container as the primary functions of the pier member 28 are that of centrally tying together the roof and floor portions and supplying to the container sufficient rigidity or resistance to longitudinal forces active thereon to thus maintain symmetry or parallelism of the container 11 during operational use thereof. In this respect the pier member 28 may merely include the vertical panels 30 extending between fixed attachment with opposite side marginal portions of both the floor portion 24 and roof portion 27. Of course other suitable arrangements of rigidifying means may be used. In this same respect the intermediate spacer posts 29 extend between the floor and roof portions in fixed attachment therewith but other suitable means may be used if additional intermediate supports are necessary.

The container 11 is basically completed by the provision of a plurality of longitudinally sliding door sections 32. These sections are located along opposite sides of the container and provide side closures therefor. The door sections 32 are suspended from the roof portion 27 and are not fixed to or supported by the floor portion 24 thereby not constituting structural stress members of the container. In this respect the door sections 32 are merely side closures and are not designed as load bearing members during operational stressing of the container. The door sections are slidably into overlying relation to provide for substantial areas of access into the container from either side thereof. Suitable lock members 33 are provided on the end walls 26 and pier mem-

ber 28 for maintaining door sections 32 in their closed positions as illustrated in FIG. 1.

The schematic illustration of FIGS. 33 and 35 and 36 is designed to graphically illustrate the basic principles of the special container car structure. It will be understood that FIG. 35 illustrates an exaggeration of the deflection of the container car under load conditions to emphasize the underlying principles of construction and operation as more fully to be described hereinafter.

10 The container 11 of FIGS. 2 and 35, and 36 is illustrated with the door sections 32 removed, it being borne in mind that the door sections are not stress members and merely function as side closures. Thus the basic components of the container car include the underframe 10 having the roller assemblies 18 and wheel trucks 14, and the container 11 including the floor portion 24, end walls 26, roof portion 27, center pier member 28 and intermediate spacer posts 29. FIGS. 35 and 36 illustrate the use of pivotal connections 34 defining the attachments of the rigid end walls 26 with the floor portion 24 and roof portion 27. Additional pivotal connections may also be provided at opposite ends of the spacer posts 29 to define their attachments with the floor and roof portions if desired. However, the center pier member 28 remains a rigidly connected member with relation to the roof and floor portions at least in a longitudinal direction.

20 Still referring to FIGS. 34 and 35, the load 35 received within the container 11 provides for deflection thereof and deflection of the underframe 10 as more fully to be described hereinafter. It will be apparent that the container 11 no longer functions as a unitary stress member with the end walls 26 pivotally interconnected with the floor and roof portions. Under such circumstances 25 both the floor and roof portions are deflected about their own respective neutral axes and the end walls 26 remain vertically related. With this arrangement the stiffness of the floor and roof portion may be considerably reduced and the over-all stiffness of the container 11 is materially reduced. The roof portion 27 is no longer a compression member and therefore is not required to resist bending but it is intended merely to flex in response to the load 35. Similarly, the floor portion 24 is no longer a tension member and is readily flexible to deflect in response to the load 35. Neither the floor nor roof portions transmit any bending stresses to the end walls 26 and the total strength of these walls is available to resist longitudinal forces arising from operation of the container car. Consequently, the floor and roof portions 30 especially, and even the end walls, may be materially reduced in section thus considerably reducing the over-all weight of the container 11 and the cost of fabrication thereof. The arrangement described basically permits practical use of a long container thus realizing substantial space-saving for efficient payload utilization of a railway car.

30 FIG. 3 illustrates the end of the underframe 10 adjacent one of the truck ends thereof. The underframe is formed with a relatively shallow elevated center sill end portion 36, a sloping intermediate portion 37 and a deeper and lower elongated center portion 38. The raised shallow end portions 36 include the outriggers 17 which are in the form of I-beams and which have suitably fixed thereto in recessed relation the roller assemblies 18. The rack beam members 20 are adapted to be received in supported relation on the inboard roller assemblies 18 as previously described, whereas the side beams 25 of the container floor portion are adapted to be received in supported engagement on the outboard roller assemblies 18. The container 11 is tied to the underframe 10 by any suitable number of hold-down brackets 39 fixed to any number of the outriggers 17 and, as illustrated in FIG. 3, overlapping the inner bottom flange portions of the container side beams 25. The brackets 39 each include bottom surface and outer end face wear pads 40

arranged for sliding engagement with wear strips 41 carried on adjacent opposed surfaces of the beams 25. The container 11 is movable longitudinally of the underframe 10 on the roller assemblies 18 as controlled by the cushion assembly 23 to be described.

FIG. 4 illustrates the deep center portion 38 of the center sill 13 with the outriggers 17 being composed of interconnected outwardly converging beam members. The roller assemblies 18 are mounted on the top surfaces of the outriggers and are horizontally aligned with the roller assemblies 18 of the opposite end portions 36 of the center sill.

FIGS. 5-8 illustrate the structural components of the end walls 26, floor portion 24 and roof portion 27. Each end wall 26 is simply constructed from a plurality of transversely spaced, vertically extending Z-shaped beams 42 having attached to the flanged end portions thereof an inner cover sheet 43 and an outer cover sheet 44 (FIGS. 7 and 8). Opposite ends of each beam 42 are interconnected by the pivot connections 34 to beam members forming a part of the floor and roof portions. Referring particularly to FIG. 5, the floor portion 24 consists basically of a plurality of channel sections 44 extending transversely thereof and constituting a known type of nailable steel floor structure such as disclosed in Patent No. 2,910,016. The channel sections 44 are supported by the longitudinal beams 20 and 25 and, by reason of the transverse extension of the channel sections, the floor portion 24 is readily flexible. A coping or finishing strip 45 extends longitudinally along each side of the floor portion in overlapping relation with the floor channel sections 44 to provide a finish to the structure.

Opposite ends of the floor portion include transverse angle beams 46 fixed to the beams 20 and 25 and being attached to the vertical beams 42 of the end wall structures. The form of pivotal connections 34 between the end wall 26 and floor portion 24 shown in FIG. 5 is merely illustrative of a suitable connection. Each illustrated connection includes an attachment plate 47 extending vertically within the angle beam 46 and fixed to the base and vertical wall portion thereof. The bottom end of each wall beam 42 associated therewith is suitably slotted or otherwise shaped, as designated by the numeral 48, to clear the vertical wall portion of the angle beam 46 for movement relative thereto. The outer portion of each beam 42 extends into engagement with an attachment plate 47 and the bottom end 49 of each beam 42 terminates short of the base portion of the angle beam 46 in vertically spaced relation thereto for at least slight movement relative thereto. Bolts 50 supplied with washers 51 interconnect the bottom end portions of the end wall beams 42 with the attachment plates 47. Sufficient clearance is provided in the slotted areas 48 and at the bottom ends 49 of each of the beams 42 to permit the end wall 26 to pivot at least slightly relative to the angle beam 46 and the floor portion 24 to maintain the vertical positioning of the end wall 26 under load deflection conditions as graphically illustrated in FIG. 2. It will be noted that half of the beam members 42 of the end wall 26 are reversed so as to vary the direction of the flanged portions thereof.

As best illustrated in FIGS. 6-8, the roof portion 27 is constructed similarly to the end walls by use of a plurality of transversely spaced and longitudinally extending Z-shaped beams 52 which have fixed thereto an outer cover sheet 53 and an inner cover sheet 54. Adjacent ends of the beams 42 and 52 overlap one another at right angles with the beams being related to one another so that the flange portions thereof do not abut or otherwise interfere thus avoiding a rigid connection. Outer surfaces of the overlapping center web portions of the beams 42 and 52 have fixed thereto reinforcing or wear plates 55 and bolts 56 extend through the overlapping ends of the beams and through the reinforcing plates to define pivot pin connections therebetween. A transverse

cover sheet angle member 57 may be suitably fixed to the outer cover sheets 44 and 53 as shown in FIGS. 7 and 8 to seal off the interior of the container. It will be understood that the cover sheets referred to, including the angle member 57, are not structural members and are quite flexible thus constituting a "skin" covering for the various wall portions. In this respect the cover sheets do not interfere with adequate relative movement between the walls of the container.

From the foregoing it will be seen that the end walls 26 and roof portion 27 are of uncomplicated, lightweight and low cost construction. The beams 42 of the end walls 26 are preferably of sufficient strength to impart rigidity to the end walls within the confining margins thereof thus avoiding bowing thereof in response to the force of loading thereagainst during operation of the car. The beams 52 of the roof portion 27 need not be of comparable strength in that the roof portion merely constitutes a cover for the container and is intended to be flexible for deflection of the container as illustrated in FIG. 2. The pivotal connections 34 are preferably designed to provide only slight relative movement between the interconnected walls of the container, such as on the order of approximately 0 to 2 degrees. Actually, in certain instances it may not be essential that distinct pivoting between the interconnected beam members is present as long as there is sufficient "play" existing in the areas of attachment between the end walls and roof and floor portions. The pivot pin connections are aligned with the axes of pivotal "play" extending transversely of the container.

FIG. 9 illustrates the center pier member 28 and the mounting thereof on the floor portion 24. As previously described, the center pier member 28 includes a pair of oppositely positioned, vertically extending rigid panels 30 rigidly interconnected at the tops thereof by the transverse panel 31. The base of each vertical panel 30 is fixed to a side beam 25 by a base structure 58 which is received within the recessed side portion of the beam 25 fixed between the top and bottom flanges thereof. The panels 30 and 31 may be of any suitable construction as long as they are of sufficient rigidity to provide adequate resistance to longitudinally directed operational forces thus providing the container 11 with adequate rigidity and retain the symmetry thereof. In this respect the pivotal attachments of the end walls and floor and roof portions in the absence of means supplying rigidity to the container would result in lack of adequate structural strength in the container to resist longitudinally applied operational forces. The center pier member 28 makes up for the lack of rigidity in the container without interfering with the advantages gained from pivotal end wall connections. Furthermore, the center pier member 28 does not interfere with adequate and substantial access to the interior of the container for load receiving and removal purposes. The center pier member additionally functions to support the roof sections 27 and maintains parallelism between opposite wall members of the container during deflection under load conditions as illustrated in FIG. 34.

Each panel 30 of the center pier member 28 along the outer surface thereto and centrally thereof includes a pair of recessed areas 59 in which the door section lock members 33 are pivotally mounted. The particular location of the center pier member 28 permits the use thereof as an intermediate door post for sealing and locking of adjacent sections 32. The transverse top panel 31 as shown in FIGS. 6 and 9 is formed with a plurality of longitudinally projecting attachment plates 60 suitably fixed to adjacent ends of the beams 52 of the roof portion 27. The segments of the roof portion 27 on opposite sides of the panel 31 may be rigidly fixed to the panel as the roof segments are sufficiently inherently flexible to provide for the bending thereof necessary in efficient operational use of the container. However, limited pivotal connections 75 may be provided as a substitute for the fixed connections

of the roof segments with the center pier member 28 if desired. The center pier member 28 functions in co-operation with the vertical rigidity of the end walls 26 to maintain and support the roof portion 27 in parallelism with the floor portion 24.

FIG. 10 illustrates one of the spacer posts 29 and its operative connection with the container 11. The spacer posts 29 are located in transversely paired relation on opposite sides of the container intermediate the center pier member 28 and the end walls 26. The spacer posts 29 function primarily to support the segments of the roof portion 27 in view of the substantial length of the container 11. The spacer posts 29 may be in the form of box-shaped beams exhibiting adequate longitudinal rigidity to provide adequate support for the roof portion. However, the end attachments of the spacer posts should permit some torsional action therein to accommodate the deflection of the floor and roof portions under load conditions as illustrated in FIG. 2. In this respect FIG. 10 illustrates the bottom end of each post 29 being fixed to a projecting end of a beam 61 extending transversely of the container under at least the adjacent longitudinal beam 25. Each beam 61 may, depending upon its shape and size, extend continuously across the undersurface of the container 11 as long as the location thereof does not interfere with proper mounting of the container on the roller assemblies 18 of the underframe 10. The transverse beams 61 are fixed to at least some of the longitudinal beams 20 and 25 but are subject to twisting, or at least the spacer posts 29 can bend relative thereto, to a sufficient extent to accommodate deflection of the floor and roof portions in the manner previously described. The top end of each spacer post 29 is attached to a plate 62 extending continuously transversely across the top of the container 11 and fixed to the top cover sheet 53 of the roof portion 27 as shown in FIG. 6. Here again, the member 62 or at least the top end of each spacer post 29 attached thereto may be subjected to stressing to accommodate the deflection of the container.

In certain instances it might be desirable to utilize spacer posts which are pivotally connected at opposite ends to the container 11 and thus capable of being free from stressing during deflection of the container while still performing their basic function of supporting the roof portion 27 intermediate the end walls and center pier member. FIG. 11 illustrates a pivotally connected spacer post 63 provided at the bottom end with a channel portion 64 receiving a pivot pin 65 therethrough, the pivot pin extending through a vertical ear 66 supported on the transverse beam 61. The top end of the spacer post 63 includes a channel portion 66 receiving a pin 67 therethrough which is also received through a depending ear 68 fixed to the top transverse member 62. With this arrangement each spacer post 63 is isolated from stresses during load deflection of the container 11 and is free to move relative to the floor and roof portions of the container while still functioning to space the same and support the roof portion.

FIG. 12 illustrates a central portion of the floor portion 24 as including a removable cover section 69 permitting access to the cushion assembly 23 as shown in FIG. 14. As previously described, the floor portion 24 may preferably be formed from channel sections 44 of a known type of nailable floor construction. FIG. 13 briefly illustrates this type of construction which is fully disclosed in the aforementioned patent. The channel sections 44 are inverted and supported by intermediate angle members 70 extending longitudinally thereof. The floor portion 24 may include a bottom cover plate 71 extending continuously thereof between the various elements of the nailable floor construction and the supporting top surfaces of the beams 20 and 25. The channel sections 44 are shaped along adjacent side margins thereof to provide for tortuous slot-like recesses 72 in which lading attaching nails may be driven and retained. Ad-

jacent channel sections 44 are fixed relative to one another by spot welds 73 which are spaced along the nail-receiving slots 72.

The cover section 69 includes a plurality of channel section segments conforming exactly to the surrounding nailable floor construction and being merely transversely interrupted from adjacent channel sections 44 in defining the separated margins of the cover section. The margins of the floor portion 24 along the opposite ends of the opening receiving the cover section 69 are defined by channels 74 of generally C-section supported on the bottom cover plate 71. The channel sections 44 forming a part of the cover section 69 are supported on a bottom cover plate 75, this bottom cover plate being attached to the cover section 69 by a plurality of brackets 76. The brackets 76 are fixed to the cover plate 75 and selected channel sections 44 are fixed thereto through fasteners 77. The channel sections 44 of the cover section 69 are of course fixedly interconnected through the spot welds 73. The opposite end channel sections 44 of the cover section 69 include outward projecting attachment portions 78 which overlap the top surfaces of the adjacent channels 74. Removable fasteners 79 secure the cover section 69 to the floor portion 24. Removal of the fasteners 79 permits ready separation and removal of the cover section 69 thus permitting access to the cushion assembly located directly therebelow as illustrated in FIG. 14. With the cover section 69 in place, the entire area thereof can be used for lading attachment purposes in the same manner that the remaining portion of the floor portion 24 can be used.

Referring to FIG. 14, the cushion assembly is of known type including a hydraulic force dissipating means 80 provided at opposite ends thereof with end plates 81. To each side of the hydraulic cylinder 80 is a return spring 82 suitably confined between opposite end plates 83. Compression of this assembly in either direction results in contraction of the hydraulic cylinder 80 as well as the springs 82 with the cylinder functioning in the known manner to dissipate or absorb to a substantial degree the force of impact causing such compression.

FIGS. 1, 15 and 16 illustrate the spaced stop members 19 carried on the top surface of the center sill 13 of the underframe. While any suitable stop member may be utilized, the particular form of stop member illustrated includes a block-like body portion having mounted along the top surface thereof three transversely spaced and vertically projecting stop blocks 84. FIGS. 15 and 17 illustrate the stop members 22 of the rack assembly 12 as being in the form of upwardly opening channel members having fixed along the bottom surfaces thereof a plurality of transversely spaced block members 85. As best shown in FIG. 15, the block members 84 and 85 are spaced relative to one another to be arranged in vertically overlapping relation with adequate space between adjacent block members 84 and 85 to permit ready relative movement between the rack assembly 12 and the underframe 10. The block members are also arranged for end engagement with the elements of the cushion assembly 23 with end surfaces of the block members engaging adjacent end surfaces of the end plates 81 and 83.

As previously described, the rack assembly 12 is fixed to the floor portion 24 of the container 11 and is supported on the underframe 10 by the roller assemblies 18. The cushion assembly 23 is confined between the vertically overlapping block members 84 and 85 of the spaced stop members 19 and 22 of the underframe and rack respectively. Thus upon movement of the underframe 10 relative to the container 11 in one direction as a result of an end impact, the stop member 19 adjacent the end to which the impact is applied will move longitudinally away from the adjacent stop member 22 of the rack assembly 12 and will compress the cushion assembly 23 against the oppositely spaced stop member 22 of the rack assembly 12. In this manner the hydraulic cylinder 80 will contract and function to dissipate the energy of

impact and will also function to controllably apply a portion of the energy to the container 11 through the opposite end stop blocks 85 thus providing for controlled and uniform acceleration of the container 11 without accompanying lading damage.

FIGS. 18 and 19 illustrate the basic structural features of the door sections 32. The container 11 in the form illustrated includes a total of four door sections on each side thereof with the door sections being arranged in pairs located between the center pier member 28 and an end wall 26. Each door is supported along its top edge in suspended relation from the roof portion 27 and the door sections of each cooperating pair are arranged in adjacent end overlapping relation in the closed condition thereof and mounted in separate track means for movement into and out of mutual and coextensive overlying relation. One door section is sealed and locked with an end wall and the cooperating door section is sealed and locked with the center pier member 28 using the lock members 33 carried by the end walls and the center pier member. In the open condition of the container, approximately one-half of the total area of each side of the container can be made available for lading transferring purposes. This arrangement provides for substantial access to the interior of the container along either side thereof.

Each door section 32 is of lightweight construction as these sections function merely as side closures and not as stress members forming a part of the container structure. The door section illustrated in FIG. 18 may for example be the rearmost door section as viewed in FIG. 1 arranged for locking arrangement with the rearmost end wall 26 whereas the door section 32 of FIG. 19 may be the cooperating paired door section arranged for movement relative to the door section of FIG. 18 in overlapping relation therewith and for sealing engagement with the rearmost edge portion of the center pier member 28 as viewed in FIG. 1. Each door section includes a vertical lead post 86 provided with a vertically continuous sealing flange 87 and an outwardly exposed recessed area 88 designed to accommodate door lock and sealing arrangements as will be described. The opposite end of each door section is defined by a vertical end post 89 having a right angled flanged end surface portion 90 and also provided with an outwardly exposed recessed area 91 for door lock and sealing arrangement mounting. Each door section intermediate the lead and end post thereof includes a plurality of vertical rib members 92 to the outer surface of which cover sheets 93 are attached and extend along the inner and outer surfaces of the door section. As the door sections are not stress members of the container 11, the same may be formed from lightweight material, such as aluminum or the like, the various end and intermediate posts being formed by extrusion. Basically, the lead posts 86 of the cooperating overlying door sections of FIGS. 18 and 19 are adapted to be moved into sealed and locked relation with the center pier member and one of the end walls with the end posts 89 being retained in overlapping relation in association with a spacer post 29 generally directly inwardly of the same.

FIG. 20 illustrates a side margin of the roof portion 27 as including a continuous door section suspension and guide track housing 94 of generally inverted L-shaped suitably fixed to the roof portion. The track housing 94 includes an inner vertical wall portion 95 formed with a bottom outwardly directed track flange 96, an intermediate outwardly projecting track flange 97 formed at the outer end thereof with a depending guide flange 98 and a further outwardly positioned depending seal flange 99, and an outwardly projecting top cover flange portion 100 including as parts thereof a pair of spaced depending guide flanges 101 and an outwardly positioned depending seal flange 102. The track housing 94 may be formed from extruded aluminum as the same functions to sup-

port the lightweight door sections 32 and as a part of the roof portion does not become subjected to compressive stress.

Each door section 32 along the top edge thereof is defined by a longitudinal hanger member 103 which may also be in the form of an aluminum extrusion and which includes an attachment flange portion 104 provided with an upwardly extending seal flange 105. A plurality of longitudinally spaced roller castings 106 are fixed to the flange portions 104 of the top members 103 of the door sections. Each roller casting 106 includes a vertically positioned inner support roller 107 and an elevated horizontally extending guide roller 108. The rollers of each casting are mounted for rotation about stub shaft portions forming a part of the casting and are arranged in closely spaced relation to one another for cooperative functioning. The support roller 107 of the innermost door section 32 as viewed in FIG. 20 is supported on the flange track 96 for operation therewith. The guide roller 108 is received between the inner vertical wall portion 95 and the depending guide track 98 in slightly spaced relation thereto to function in maintaining the door section within the track housing 94 and yet permit free movement thereof along the track housing. The support roller 107 of the outermost door section 32 as viewed in FIG. 20 is supported on the track portion 97 and the guide roller 108 associated therewith is loosely received between the depending guide flanges 101. This door section functions in the same manner as the associated door section previously described. The vertical sealing flanges 105 of each door section project into the sealing areas of the track housing 94 between the depending flange portions 98 and 99, and 101 and 102. This sealing arrangement is in the form of a labyrinth to aid in preventing the fouling of the rollers thus providing for continued efficient operation of the door sections.

FIGS. 21 and 22 illustrate the bottom seal and guide arrangement for the door sections 32. Along the outer side surface portions of the floor portion of the container, specifically the side beams 25, a plurality of longitudinally spaced series of guide rollers are mounted along the outer bottom flange portion 109 of each side beam 25. Each assembly of guide rollers includes a horizontal supporting plate 110 fixed to the flange 109 and carrying a plurality of transversely spaced and arranged support brackets 111 having mounted thereon guide rollers 112 arranged to rotate about vertical axes defined by fasteners 113. Each door section along the bottom margin thereof is provided with a longitudinal member 114 having formed integrally therewith a sealing skirt flange 115 which extends downwardly therefrom, inwardly under the top flange portion 116 of the side beam 25, and then downwardly between the rollers 112 in engagement with at least one roller. Flanges 115 are adequately spaced from one another and from engagement with the floor portion to permit free sliding operation of the door sections.

The flanges 115 extend substantially downwardly to provide for an adequate seal along the bottom side margins of the container. In this respect the flanges project inwardly within the outwardly exposed recessed area of the side beams 25 between the top and bottom outer flange portions 116 and 109 thereof and not only completely seal the container but also do not project outwardly from the side margins of the container. With this arrangement the door sections 32 are freely movable along the sides of the container and are not fixed thereto to an extent that they function as stress members. FIG. 22 illustrates one of the base portions of a spacer post 29 and its connection with the transverse beam 61 interconnecting a pair of spacer posts across the bottom surface of the container 11. This view also illustrates the positioning of the guide rollers 112 relative to the spacer post 29 along the sides of the container.

FIGS. 23-25 illustrate one of the lock members 33 mounted on the center pier member 28 and cooperating

with an adjacent door section 32. The lock member includes a plate-like latch portion 116 provided with a hook-like end portion 117 having a recess 118 adapted to be received about a locking pin 119 fixed in the recessed area 88 of the lead post 86 of the door section 32. As best shown in FIG. 24, the pin 119 has an enlarged outer head portion 120 forming a part thereof to confine the hook end 117 of the latch portion thereon, the pin extending inwardly through a pair of spaced plates 121 which are fixed to a base plate 122 which in turn is suitably fastened within the recessed area 88. The pin 119 intermediate the plates 121 has fixedly received thereabout a plate 123 forming a part of a starter handle 124 which extends outwardly from the outer surface of the door section 32 adjacent the end of the latch portion 116 and is available for grasping to start movement of the door section upon unlocking thereof. The innermost plate 121 includes a car seal portion 125 and the latch portion 116 includes a cooperating car seal plate portion 126 as best shown in FIG. 25.

The latch portion 116 includes at one end thereof a generally U-shaped housing 127 received in the recessed area 59 of the center pier member 28 as best shown in FIG. 24. The housing 127 slidably receives therein a cam lock member 128 formed from a pair of parallel and spaced plates 129 interconnected at one end by a filler member 130 receiving therethrough and through the overlying ends of the plates 129 a pivot pin 131 suitably fixed to the panel 30. With this arrangement the cam member 128 is pivotal about the pin 131. The opposite end of the cam member 128 is closed by a cam track member 132 having an inclined surface facing toward the pivot pin 131. The plates 129 as best shown in FIG. 25 are formed with aligned elongated apertures 133 and receive therethrough a transverse pin 134 which is fixed in the U-shaped housing 127 of the latch portion. With this arrangement the latch portion 116 is longitudinally slidable relative to the cam member 128 within the confines of the elongated apertures 133. A locking cam 135 is movably received between the plates 129 of the cam member 128 and is provided with a circular aperture 136 (FIG. 25) through which the pin 134 is received and about which the cam 135 pivots. The leading surface 137 of the cam 135 is arcuate and arranged for sliding engagement with the cam track member 132 when the cam 135 is forced downwardly. A projecting portion 138 is formed on the cam 135 to permit ready engagement thereof for operation into and out of wedging locking position.

FIG. 23 illustrates the lock member 33 in its door section locking position. The end portion 117 engages the pin 119 of the door section 32 with the pin being received in the locking recess 118. The cam 135 is forced downwardly with the arcuate camming surface 137 thereof tightly engaging the inclined cam track member 132 with the result that the latch portion 116 is forced rearwardly in telescoping relation relative to the cam member 128 toward the pivot pin 131. This movement is accommodated by the elongated apertures 133 in the plates 129 of the cam member 128. The close pivotal fit of the cam 135 about the pin 134 forces the latch portion 116 rearwardly toward the pivot pin 131 when the cam 135 is moved downwardly into the position shown in FIG. 23. Unlocking is brought about by the raising of the cam 135 as shown in FIG. 25 thus releasing the latch portion 116 for sliding movement relative to the cam member 128 as permitted by the elongated apertures 133. This permits extension of the latch portion 116 to an extent that it can be readily disengaged from the locking pin 119 of the door section 32.

The vertical side marginal portion of the center pier member 28 has fixed thereto a vertically continuous sealing member 139 as best shown in FIG. 24. The sealing member is of any suitable outwardly opening configuration adapted to receive therein the sealing flange portion 87 of the lead post 86 of the door section 32.

FIGS. 26 and 27 illustrate the mounting of a latch member 33 in operative relation between an end wall 26 and an adjacent door section 32. The outer side margins of each end wall 26 include a bracket 140 fixed thereto 5 mounting the pivot pin 131 of the latch member 33. Each side margin of an end wall 26 also includes a vertically continuous sealing member 139 arranged to receive therein the sealing flange portion 87 of the adjacent door section 32. In all other respects the mounting and operative use of the end wall latch members 33 are the same as previously described.

FIGS. 28-32 illustrate a special form of door section sealing arrangement forming a part of the invention and used in sealing the overlapping end portions of the door sections in their closed condition. As previously described, the end posts 89 of the door sections 32 are arranged in marginal overlapping relation vertically of the door sections when the doors are closed and locked as shown in FIG. 1. Referring particularly to FIG. 28, 20 the innermost door section 32 in the recessed area 91 of the end post 89 thereof has mounted therein a transverse pin 141 aligned with an aperture 142 formed in the end post 89 immediately rearwardly of the pin 141. Opposite ends of the pin are fixed in mounting plates 143 received 25 in the recessed area 91 and attached to the end posts by fasteners 144. A plurality of vertically spaced pins 141 are provided with each end post 89.

The overlapping outwardly positioned end post 89 of the cooperating door section 32 has received in the recess 91 thereof a pin 145 mounted in a clamping member 146 attached by fasteners 147 to the end post 89. The pin 145 extends outwardly through the flanged end wall portion 90 and attaches thereto a vertically continuous seal assembly 30 including a flexible sealing strip 148 arranged in inwardly opening U-shape with one marginal portion thereof fixed about the pin 145, clamp 146 and end wall portion 90 and the other marginal portion thereof projecting inwardly toward the adjacent door section 132 and defining a vertically continuous flexible sealing flange portion 149. The sealing strip 148 is fixed to a bracket 150 at the base thereof, the bracket including arms 151 and 152. As best shown in FIGS. 31 and 32, the arm 151 is formed with a slot 153 therein in which a pin 154 is received, this pin being fixed in a transverse aperture 155 in a hook member 156. The hook member 156 is fixed to the pin 145 for pivoting therewith whereas the bracket 151 is slidable relative to the hook member 156 for reciprocation relative thereto as controlled by the pin 154 received in the slot 153. The remaining arm 152 is formed with a recess 157 (FIGS. 31 and 32) received about the pin 145 to be readily movable toward and away from the same upon pivoting of the pin 145. The hook member 156 as best shown in FIGS. 31 and 32 is formed with a hook portion 158 adapted to be received about the pin 141 of the underlying door section 32 in the operative position of the sealing member 148.

The opposite end of the pin 145 projects from the bracket 146 and has fixed thereto an operating lever 159 which projects radially outwardly from the door section 32 carrying the same. The operating lever 159 at the outer end thereof is bifurcated receiving therebetween a vertically continuous unlocking rod 160 which as best shown in FIG. 29 consists of a plurality of vertically spaced flattened portions 161 which are received between the bifurcated ends of each lever 159. In this respect it will be understood that the various elements described including the pins 145 and hook members 158 are vertically duplicated along the door sections with the unlocking rod 160 extending therebetween to operatively interconnect the same.

The flattened portions 161 of the unlocking rod are pivotally attached to the levers 159 by a fastener 162 which at one end thereof has fixed thereto a locking handle 163. As shown in FIG. 29 the top end of the locking handle 163 projects upwardly beyond the fastener 162 to a suffi-

cient extent to overlap a fixed projecting pin 164 (FIG. 28) carried by the lever 159. In this respect the pivotal lifting of the handle 163 will result in the projecting top end portion thereof engaging the fixed pin 164 providing a fulcrum point for lifting of the lever 159 accompanied by limited rotation of the pin 145. The rod 160 transmits this lifting motion of the lever 159 to which the handle 163 is attached vertically of the door assembly thus providing for simultaneous lifting of the additional levers 159 and simultaneous pivoting of the pins 145 vertically of the door assembly. The pivoting of the pins 145 results in the pivoting of the hook members 158 from the unlocked position shown in FIG. 31 into the locked position shown in FIG. 32 wherein the hook end portions engage the associated pins 141 of the adjacent door section. Rotation of the hook members in a counterclockwise direction as illustrated in FIGS. 31 and 32 results in accompanying arcuate movement of the pins 154 in the slots 153 and a drawing inwardly of the brackets 150 with the attached sealing member 148 moving inwardly therewith toward the underlying end portion of adjacent door section 32. Thus the sealing member 148 moves from the inoperative position shown in FIG. 28 into the operative position shown in FIG. 30 with the flexible sealing flange portion 149 placed in sealing engagement with a surface of the underlying end portion of the adjacent door section 32.

Following the locking operation of the sealing assembly, the multiple hook members 158 function adequately to hold the sealing member in operative position during operational use of the car. When it is desired to unlock the sealing arrangement, it is necessary merely to grasp a portion of the unlocking rod 160 intermediate adjacent levers 159 and pull the rod downwardly so that the interconnected pins 145 are pivoted in a clockwise direction as viewed in FIGS. 21 and 32. This reverse operation results in disengaging lifting of the hook members 158 accompanied by upward and outward arcuate movement of the pins 154 with the result that the brackets 150 will move outwardly and disengage the flexible sealing flange portion 149 from the adjacent underlying door section. This arrangement permits elimination or reduction of the sealing pressure of the sealing member of the sealing strip 148 applied against the underlying door section 32 when it is desired to move the doors relative to one another for access into the container. In this manner a very efficient door section seal is provided between overlapping end portions of door sections, the seal being readily adjustable in its relation to the door sections to permit relative movement of the door sections without interference from the sealing member.

Suitable door section keeper arrangements including door hooks 165 and brackets 166 may cooperate between the brackets 146 and the spacer posts 29 as shown in FIGS. 28, 31 and 32. The keeper arrangements may be associated with each bracket 146 in spaced relation vertically of the door sections if desired thus providing an adequate degree of lateral stability thereto during operational use of the car. The depending ends 167 of the hooks 165 are closely received between the outer bracket portion 166 and an abutment member 168 mounted along the inner surface of the adjacent spacer post 29. The free ends of the bracket 166 and plate 168 may be formed with beveled inner surface portions 169 to readily accommodate the receiving of the depending end 167 of the hook 165.

Referring now in particular to FIGS. 2, and 33-41, as heretofore discussed in greater detail, the container 11 is basically completed by the provision of a plurality of longitudinally sliding door sections 32 shown in FIG. 1. These door sections are located along opposite sides of the container and provide side closures therefor. The door sections 32 are preferably suspended from the roof portion 27 and are not fixed to or supported by the floor

portion 24 thereby not constituting structural stress members of the container. In this respect the door sections 32 are merely side closures and are not designed as load bearing members during operational stressing of the container. The door sections are slideable into overlying relation to provide for substantial areas of access into the container from either side thereof. FIG. 2 illustrates the container 11 with the door sections 32 removed for a better understanding of the basic structural features of this particular embodiment of the container.

The schematic illustrations of FIGS. 33-41 are designed to graphically illustrate the basic concepts of the present invention and it will be understood that those views illustrating deflection of the container cars are exaggerated to best illustrate the underlying principles.

FIG. 33 illustrates the container car and its basic components to be referred to in describing the principles of the invention. The container 11 is illustrated in the open form of FIG. 2, it being borne in mind that the door sections 32 are not stress members and merely function as side closures. Thus the basic components illustrated include the underframe 10 including the roller assemblies 18 and wheel trucks 14, and the container 11 including the floor portion 24, end walls 26, roof portion 27, center pier member 28 and intermediate spacer posts 29. The car in FIG. 33 is in its unloaded condition wherein basically the underframe 10 and container 11 are not subjected to stresses.

FIG. 34 illustrates a load deflection condition of a container car of the type described if the container 11 were to be constructed as a rigid unitary member. In accordance with conventional container construction, the various wall portions including the ends, sides, floor and roof cooperate in rigidly interconnected relation to accommodate stresses such as caused by loading or the like. Thus if the container 11 were to be constructed with rigid connections between the various basic wall portions thereof as is conventional, the loading of the container as illustrated by the load 35 would result in the entire container acting as a single unit under load with the roof portion 27 in compression and the floor portion 24 in tension. FIG. 34 illustrates the existence of a single neutral axis C for the rigid form of the container 11 thus requiring shortening of the roof portion 27 and extension of the floor portion 24 under tension.

It would at least be exceedingly expensive, if not extremely difficult, to construct a long container of the type illustrated in the form of a completely self-sustaining rigid unit having a single neutral axis as illustrated in FIG. 34. In this respect the length of such a container may be on the order of 78 feet and with such length it can readily be appreciated that an adequately rigid container would require a substantial amount of material and exhibit a substantial total weight. In order to overcome these disadvantages thus permitting practical fabrication and use of a container of such extensive length, the over-all rigidity of the container 11 is reduced by the provision of means permitting at least limited relative movement between at least some of the basic structural members thereof as shown in FIGS. 35 and 36.

FIG. 35 illustrates the use of pivotal connections 36 defining the attachments of the rigid end walls 26 with the floor portion 24 and roof portion 27. As heretofore described, additional pivotal connections 65 may also be provided at opposite ends of the spacer posts 29 to define their attachments with the floor and roof portions. However, with the use of the center pier member 28 in some of the forms of the invention, this member remains a rigid member having rigid connections with the floor and roof portions at least in a longitudinal direction.

From a comparison of FIGS. 4 and 5, it will be apparent that the container 11 no longer functions as a unitary stress member when the end walls 26 are pivotally interconnected with the floor and roof portions. Under such circumstances both the floor and roof portions are

deflected about their own respective neutral axes, the neutral axis F being that of the floor portion 24 and the neutral axis R being that of the roof portion 27. With this arrangement the stiffness of the floor and roof portion is considerably reduced and the over-all stiffness of the container 11 is also materially reduced. The roof portion 27 is no longer a compression member and therefore is not required to resist bending but is intended to merely flex in response to the load 35. Similarly, the floor portion 24 is no longer a tension member and is readily flexible to deflect in response to the load 35. Neither the floor nor roof portions transmit any bending stresses into the end walls 26 and the total strength of these walls is available to resist longitudinal forces arising from operation of the container car. Consequently, the floor and roof portions especially, and even the end walls, may be materially reduced in section thus considerably reducing the over-all weight of the container 11 and the cost of fabrication thereof. The unique arrangement described basically permits practical use of a long container thus realizing substantial space saving for efficient payload utilization of a railway car.

The design concept of FIG. 36 is basically similar to that of FIG. 35 except that the pivotal connections 65 of the spacer posts 29 are eliminated. The primary function of the spacer posts 29 is that of supporting and tying together the floor and roof portions intermediate the center pier member 28 and the end walls 26 to maintain symmetry of flexure in response to load. The spacer posts may be fabricated from adequately lightweight material to permit sufficient flexing thereof under load deflection conditions to accommodate the over-all deflection characteristics of the container 11 as illustrated while maintaining adequate interconnection between the floor and roof portions to carry out the basic function of these posts. Where the pivot connections 65 are utilized, the spacer posts may be of lighter weight material as the floor and roof portions do not transmit any bending stresses thereto. However, only a relatively minor material and weight savings is realized by use of the pivotal connections 65, and it is quite acceptable to provide for rigid attachment of the ends of the spacer posts to the floor and roof portions.

While the form of container 11 described above is preferred particularly with regard to its ready removability from the underframe 10, it is possible to advantageously utilize the basic principles of the invention in a railway car construction wherein the container portion is a permanent part of the car. FIG. 37 illustrates a car 237 provided with a conventional underframe 238 supported by wheel tracks 239 and having mounted thereon a container portion including vertical end walls 240, a flexible roof portion 241 and a rigid center pier member 242 extending from the roof portion into fixed connection with the underframe 238. Pivotal connections 243 define the attachments of the end walls 240 to the underframe 238 and roof portion 241. Deflection in response to the load 35 results in the end walls 240 remaining in a vertical position by reason of the connections 243 and the roof portion being merely flexed without foreshortening in the same manner as previously described in connection with FIGS. 35 and 36. In this design the underframe 238 constitutes the floor portion of the container and suitable door sections may be suspended from the roof portion 241 in the same manner as previously described without being relied upon as load bearing members. The center pier member 242 adds sufficient longitudinal rigidity to the container portion to maintain symmetry thereof in response to longitudinally directed forces of operation. If desired, an appropriate number of spacer posts may be applied between the underframe 238 and roof portion 241.

Still another modification of basic container construction is illustrated in FIGS. 38 and 39. The underframe 10 remains the same as previously described including the rollers 18. A modified form of container 244 in-

cludes a flexible floor portion 245, vertical end walls 246, a flexible roof portion 247 and a rigid center pier member 248. The rigid end walls 246 are fixedly and rigidly attached to opposite end portions of the floor portion 245 as emphasized by the provision of reinforcing web-like bulkhead end structures 249 fixed to the end walls along the outer surfaces thereof and fixed to the outer end portions of the floor portion 245. Thus the end walls 246 are not movable relative to the floor portion 245 and become at least slightly angled inwardly as shown in FIG. 39 in response to an applied load 34. The top surface portions of the end walls 246 may be provided with roller assemblies or other suitable means on which opposite end portions of the flexible roof portion 247 rest.

Upon load deflection as shown in FIG. 39 the lack of rigid connection between the end walls 246 and the roof portion 247 permits independent flexure of the roof portion 247 relative to its own neutral axis as well as independent flexure of the floor portion 245 relative to its own neutral axis. The center pier member 248 functions to tie down the central portion of the roof portion 247 and maintain its proper relation in the container construction.

Relative movement between the end walls 246 and the roof portion 247 is readily provided by the roller assemblies 250 and container continuity is maintained without the transmission of bending stresses between wall portions thereof. The roller assemblies 250 establish a sliding contact between the roof portion 247 and end walls 246 and in this manner the roof and floor portions are not rigidly interconnected. The bulkhead members securing the end walls 246 provide for a vertical cantilever reinforcement of the end walls to accommodate longitudinal forces created as a result of the car end impacts. Here again, intermediate spacer posts of the type previously described may be used if desired.

FIGS. 41 and 42 illustrate a modified form of the container design of FIGS. 38 and 39. The container 251 includes a flexible floor portion 252 end walls 253 rigidly connected to the floor portion 252 and reinforced by bulkhead members 254, and a flexible roof portion 255. One of the end walls 253 is also rigidly secured to one end portion of the roof portion 255 whereas the remaining end wall 253 is provided at the top thereof with suitable roller assemblies 256 in sliding engagement with the adjacent end portion of the roof portion 255.

FIG. 41 illustrates deflection of the modified car under a load 35. The rigid connection of one end wall 253 to the roof portion 255 may be adequate to cause bending of the same as illustrated with the free opposite end of the roof portion sliding relative to the opposite end wall 253. In this manner the roof portion 255 still functions as an independent member bending relative to its own neutral axis and the floor portion 252 continues to function independently in a similar manner. The container rigidity supplied by the fixed connection of one of the end walls 253 between both the floor and roof portions may be adequate to maintain proper symmetry of the container in response to horizontal forces developed as a result of car end impacts. Under such circumstances, the previously described center pier member may be eliminated with the rigidly interconnecting single end wall imparting adequate over-all rigidity to the container 251. Here again, the equivalence of intermediate spacer posts of the type previously described may be desirable to properly tie in the floor and roof portions depending upon the total length of the container.

One of the underlying concepts of the invention is that of providing adequate rigidity and strength to the container to accommodate longitudinal forces applied thereto during operation of the car without accompanying use of the roof portion solely as a compression member and use of the floor portion (either constituting a separate part of the container or constituting a part of the underframe) solely as a tension member. In effect, the type of container car described constitutes a load bearing under-

frame mounting thereon a load confining container portion. In this respect the container portion is not the equivalent of a conventional railway car body such as used in box cars or the like. The container portion is designed basically to merely confine the load especially in response to longitudinally directed operational forces, the container portion being wholly deflectable with the underframe thus permitting the construction and efficient utilization of a long length container portion. The provision of a floor portion as part of the container is primarily for the purpose of permitting removal of the container and the load confined therein from the car when desired. A known type of sliding sill cushioning arrangement may be used as a substitute for the cushioned rack structure described above where cushioning of a car design of the type illustrated in FIG. 37 is desired.

Obviously certain modifications and variations of the invention as hereinbefore set forth may be made without departing from the spirit and scope thereof, and therefore only such limitations should be imposed as are indicated in the appended claims.

What is claimed is:

1. A container car comprising a longitudinally deflectable underframe and a container removably mounted on said underframe, said container including a flexible floor portion which is deflectable with said underframe, spaced rigid vertical end walls attached to said floor portion, a flexible roof portion attached to said end walls and extending therebetween, said roof portion being deflectable with said floor portion and said underframe, the attachments of said end walls with said floor and roof portions including limited pivotal connection means operative about axes which are transverse of said container permitting limited pivotal movement of said end walls relative to said floor portion and said roof portion, rigid pier means extending vertically between said floor and roof portions and interconnecting the same intermediate said end walls to preclude longitudinal displacement and maintain the vertical spacing between said roof and said floor portions under load conditions, whereby said end walls and floor and roof portions at least substantially cooperatively define and maintain a paralleling relation under empty and load conditions, and side closure means suspended by said roof portion along the sides of said container and closing of the space between said end walls, said side closure means being detached from said floor portions, said underframe including container support means extending longitudinally thereof and deflectable therewith, said support means having anti-friction means in engagement with the floor portion of said container for relative longitudinal movement between said container and underframe, and impact force dissipation means interconnecting said floor portion of said container with said underframe to control said relative movement, said container extending substantially the full length of said underframe and being deflectable therewith.

2. The container car of claim 1 wherein said side closure means are in the form of a plurality of flat door sections suspended by anti-friction means supported in overhead longitudinal track means carried by said roof portion, said track means being arranged for movement of said door sections from a closed position closing the space between said end walls into mutually overlying relation to substantially expose the interior of said container along either side thereof, the bottom margins of said door sections overlapping adjacent side edge portions of said floor portions in unconfined position changing relation therewith, and means establishing a seal between said bottom margins and said side edge portions.

3. The container car of claim 1 wherein said limited pivotal connection means are each defined by a plurality of transversely spaced pin-connected overlapping sections of said end walls and floor and roof portions.

4. A container car comprising a longitudinally deflectable underframe and a container removably mounted on

said underframe, said container including a flexible floor portion which is deflectable with said underframe, spaced rigid vertical end walls attached to said floor portion, a rigid center pier member including a pair of oppositely positioned vertical panels fixed to edge portions of said floor portion and interconnected at the top portions thereof to a transverse panel, flexible roof portions attached to the transverse panel of said center pier member and said end walls and extending therebetween, said roof portions being deflectable with said floor portions and said underframe, intermediate spacer posts interconnecting said roof and floor portions along opposite side margins thereof between said end walls and center pier member, the attachment of said end walls with said floor and roof portions including limited pivotal connection means operative about axes which are transverse of said container permitting limited relative pivoting of said end walls and said floor and roof portions, whereby said end walls and floor and roof portions at least substantially cooperatively define and maintain a paralleling relation under empty and load conditions, and side closure means suspended by said roof portions along the sides of said container extending between said end walls and being detached from said floor portions, said underframe including container support means extending longitudinally thereof and deflectable therewith, said support means having anti-friction means in engagement with the floor portion of said container for relative longitudinal movement between said container and underframe, and impact force dissipation means interconnecting said floor portion of said container with said underframe to control said relative movement, said container extending substantially the full length of said underframe and being deflectable therewith.

5. A container for mounting on a vehicle chassis and adapted for vertical load deflection with said chassis, said container comprising a flexible floor portion which is deflectable with said chassis, spaced rigid vertical end walls attached to said floor portion, a flexible roof portion attached to said end walls and extending therebetween and being deflectable with said chassis and said floor portion, the attachments of said end walls with said floor and roof portions including limited pivotal connection means operative about axes which are transverse of said container permitting limited pivotal movement of said end walls relative to said floor and roof portion, rigid pier means extending vertically between said floor and roof portions and interconnecting the same intermediate said end walls to preclude longitudinal displacement and to maintain the vertical spacing between said roof and floor portions under load conditions, whereby said end walls and floor and roof portions respectively at least substantially cooperatively define and maintain a paralleling relation under empty and load conditions, side closures suspended from said roof portion extending the full length of said car between said end walls and being detached from said floor portions, said side closures including a plurality of flat door sections movably supported in overhead longitudinal track means carried by said roof portion, said track means being arranged for movement of said door sections from a closed position closing the space between said end walls into mutually overlying relation in the open condition of said container to substantially expose the interior of said container, said door sections in the closed condition of said container being arranged in end overlapping relation, sealing means vertically overlying the overlapping ends of said door sections, adjustment means forming a part of said sealing means for movement thereof into and out of sealing engagement with at least one of said door sections, and door operating means engaged with said adjustment means for actuating and operating said adjustment means, said operating means being accessible externally of said container.

6. The container of claim 5 wherein combination guide

and a support roller means are attached to said door sections along the top portions thereof and are received in said track means, the bottom portions of said door sections including depending sealing skirt means, and guide means carried along side portions of said floor portion and in engagement with said skirt means to maintain said door sections in container sealing relation.

7. A container for mounting on a vehicle chassis and adapted for vertical load deflection with said chassis, said container comprising a flexible floor portion which is vertically deflectable with said chassis, spaced rigid vertical end walls attached to said floor portion, a rigid center pier member including a pair of oppositely positioned vertical panels fixed to edge portions of said floor portion and interconnected at the top portions thereof to a transverse panel, flexible roof portions attached to the transverse panel of said center pier member and said end walls and extending therebetween, said roof portions being deflectable with said floor portion and said chassis, attachment of said end walls with said floor and roof portions including limited pivotal connection means operative about axes which are transverse of said container whereby said end walls are pivotal to a limited amount relative to said floor and roof portions to at least substantially cooperatively define and maintain a paralleling relation under empty and load conditions, and side closures suspended from said roof portions extending between said end walls and detached from said floor portion.

8. A container for mounting on a vehicle chassis and adapted for vertical load deflection with said chassis, said container comprising a flexible floor portion which is deflectable with said chassis, spaced rigid vertical end walls attached to said floor portion, a rigid center pier member including a pair of oppositely positioned vertical panels fixed to edge portions of said floor portion and interconnected at the top portions thereof to a transverse panel, flexible roof portions attached to the transverse panel of said center pier member and said end walls and extending therebetween, said roof portions being deflectable with said floor portion and chassis, the attachment of said end walls with said floor and roof portions including limited pivotal connection means operative about axes which are transverse of said container, whereby said end walls are pivotal a limited amount relative to said floor and roof portions to at least substantially cooperatively define and maintain a paralleling relation under empty and load conditions, side closures suspended from said roof portions extending the full length of said car between said end walls, said side disclosures including a plurality of flat door sections movably supported in overhead longitudinal track means carried by said roof portions, said door sections being detached from said floor portions, said track means being arranged for movement of said door sections from a closed position closing the space between said end walls into mutually overlying relation in the open condition of said container to substantially expose the interior of said container, said door sections in the closed condition of said container being arranged in end overlapping relation, sealing means ver-

5 tically overlying the overlapping ends of said door sections, adjustment means forming a part of said sealing means for movement thereof into and out of sealing engagement with at least one of said door sections, and door operating means engaged with said adjustment means for actuating and operating said adjustment means, said operating means being accessible externally of said container.

10 9. The container of claim 8 wherein combination guide and support roller means are attached to said door sections along the top portions thereof and are received in said track means, the bottom portions of said door sections including depending sealing skirt means, and guide means carried along side portions of said floor portion and in engagement with said skirt means to maintain said door sections in container sealing relation.

15 10. A container for mounting on a vehicle chassis and adapted for vertical load deflection with said chassis, said container comprising a flexible floor portion which is deflectable with said chassis, spaced rigid vertical end walls attached to said floor portion, a rigid center pier member including a pair of oppositely positioned vertical panels fixed to edge portions of said floor portion and interconnected at the top portions thereof to a transverse panel, flexible roof portions attached to the transverse panel of said center pier member and said end walls and extending therebetween, said roof portions being deflectable with said floor portion and said chassis intermediate spacer posts interconnecting said roof and floor portions along opposite side margins thereof between said end walls and center pier member, the attachment of said end walls with said floor and roof portions including limited pivotal connection means operative about axes which are transverse of said container permitting limited pivotal movement of said end walls relative to said floor portions and said roof portions, whereby said end walls and floor and roof portions at least substantially cooperatively define and maintain a paralleling relation under empty and load conditions, and side closures suspended from said roof portions extending the full length of said car between said end walls and being detached from said floor portion.
